(57) **CLAIM**

The ornamental design for an insulated beverage holder, as shown and described.

DESCRIPTION

FIG. 1 is a rear perspective view of an insulated beverage holder, showing my new design;

FIG. 2 is a rear view thereof;

FIG. 3 is a right-side view thereof;

FIG. 4 is a top view thereof;

FIG. 5 is a left-side view thereof;

FIG. 6 is a bottom view thereof; and,

FIG. 7 is a front view thereof.

The broken lines in the figures illustrate the portions of the insulated beverage holder that form no part of the claimed design.
